UNITED STATES PATENT OFFICE.

ROBERT E. CARDER, OF GREENWOOD, INDIANA, ASSIGNOR TO THE GREENWOOD PROCESS MACHINE CO., OF GREENWOOD, INDIANA, A CORPORATION OF INDIANA.

VALVE FOR PROCESSING APPARATUS.

SPECIFICATION forming part of Letters Patent No. 777,776, dated December 20, 1904.

Application filed July 3, 1903. Serial No. 164,122.

To all whom it may concern:

Be it known that I, ROBERT E. CARDER, a citizen of the United States, residing at Greenwood, in the county of Johnson and State of Indiana, have invented certain new and useful Improvements in Valves for Processing Apparatus, of which the following is a specification.

This invention relates to a combined valve and rotary conveyer for introducing and discharging canned goods from processing apparatuses, and is particularly adapted to be employed in connection with such an apparatus that forms the subject-matter of an application for patent now pending on "apparatuses for steaming and processing canned goods" filed by John Jennings on September 13, 1902, and allowed May 9, 1903, Serial No. 123,283. The receiving and discharging apertures of the processing apparatus are both provided with such a device comprising a rotary conveyer and a plurality of yieldable valve-wings that ride on the periphery of the rotary conveyers and prevent the escapement of the steam from the interior of the apparatus.

A device embodying the various features of my invention will first be fully described and then pointed out in the claims.

Referring to the accompanying drawings, which are made a part hereof, and on which similar numerals of reference indicate similar parts, Figure 1 is a top or plan view of the casing which incloses the combined valve and rotary conveyer. Fig. 2 is a horizontal central sectional view of the construction shown in Fig. 3. Fig. 3 is a horizontal sectional view on the dotted line 3 3 in Fig. 4. Fig. 4 is a front elevation of the construction shown in Fig. 1. Fig. 5 is a cross-sectional view of the same on the line 5 5 in Fig. 2. Fig. 6 is a cross-section of the construction shown in Fig. 2, and Fig. 7 is a perspective view of the floor of the housing which incloses the conveyer and relative position of the jut.

In the drawings, 1 is the rotary conveyer provided with a series of can-carrying pockets 7. These pockets extend longitudinally in the conveyer and are of a less degree of length

than the conveyer. The conveyer carries the integral head 2, which seals the upper ends of the pockets. The conveyer is provided with the shaft 4 and by means of the bevel-gears 5 and 6, the latter connecting with the driving mechanism of the processing apparatus, the conveyer 1 is operated.

The rotary conveyer 1 is housed in a suitable casing 10, which is secured to the wall 25 of the processing apparatus. The casing 10 is provided with a floor 11, which is provided with the jut or projection 12, over which the cans are discharged.

The conveyer 1 has rotary movement and is provided with the can-carrying pockets 7, which receive the cans and carry them into or out of the processing apparatus. The cans under the impulse of the conveyer are slid over the floor 11 until they reach the jut 12, when they are discharged from said floor upon the movable floor in the processing apparatus. The movement of the last-named floor with draws the cans from the pockets 7 in the conveyer 1.

A suitable delivering device 15 delivers the cans upon the floor 11 of the casing 10 and upon such delivery the cans are immediately removed by the conveyer 1 and are thence discharged into the processing apparatus.

Difficulty was experienced in introducing or discharging the cans from the apparatus by escaping steam. The steam is under pressure inside the apparatus and it escaped in such a volume at the points of introducing and removing the cans as to envelop the apparatus. The escaping steam seriously interfered with the operator in charge of the apparatus. To overcome this obstacle, I provide the rotary conveyer 1 and a series of wings 20, which act as valves. These wings are pivotally secured to the casing 10 at 21 and ride on the periphery of the conveyer. The wings 20 extend longitudinally the entire length of the conveyer 1 and circumferentially a distance sufficient to embrace one or more of the walls 3, that form the pockets in the conveyer 1. The face of the wings 20 are made to conform with the periphery of the

conveyer and are held into contact therewith by suitable tension devices 22. It will be seen by examining Fig. 2 that the wings 20 are arranged relatively to the conveyer 1, that as 5 the walls 3 pass from under the ends of the wings the succeeding walls have previously engaged them. This construction seals the openings between the casing 10 and the conveyer 1.

10 Having thus fully described my said invention, what I desire to secure by Letters Patent is—

1. In a can receiving and discharging device comprising a rotary conveyer provided with 15 a series of pockets which are of less length than the conveyer, a casing inclosing the conveyer and provided with a can-receiving aperture, means movably secured to the casing and adapted to ride on the periphery of the 20 conveyer, and means suitably arranged to operate the conveyer.
2. In a can receiving and discharging device comprising a rotary conveyer provided with a series of pockets, suitable means for operating the conveyer, a casing for inclosing the 25 conveyer, a floor provided for the casing, a jut formed in the floor for effecting the discharge of the cans from the conveyer, a plurality of wings movably secured to the casing 30 and adapted to ride on and to embrace one or more of the pockets in the conveyer.
3. In a can receiving and discharging device

comprising a rotary conveyer provided with a series of pockets, suitable means for operating the conveyer, a casing inclosing the conveyer and provided with a can-receiving aperture, a floor provided for the casing, means in the floor for effecting the discharge of the cans from the conveyer, a plurality of wings movably secured and arranged relative to the 35 40 conveyer to ride on the periphery thereof and embracing one or more of the walls that form the pockets, and means suitably arranged for holding the wings into contact with the conveyer.

4. In a processing apparatus, the combination with the frame, a can receiving and discharging device comprising a rotary conveyer provided with a series of pockets, means for operating the conveyer, a casing inclosing the 45 50 conveyer, a floor provided for the casing, jut in the floor for effecting the discharge of the cans from the conveyer, means movably secured and adapted to ride on the periphery of the conveyer for sealing the openings between the casing and conveyer.

In witness whereof I have hereunto set my hand and seal, at Indianapolis, Indiana, this 30th day of June, A. D. 1903.

ROBERT E. CARDER. [L. S.]
